Specification of Letters Patent.

Patented Mar. 16, 1915.

Application filed September 15, 1910. Serial No. 582,186.

To all whom it may concern:

Be it known that I, THOMAS J. WHALEN, a citizen of the United States of America, and a resident of New Brunswick, county of 5 Middlesex, and State of New Jersey, have invented a certain new and useful Tire-Making Machine, of which the following is a specification.

My invention relates to machines for making pneumatic tires, more especially for 10 making shoes of clincher and "quick-detachable" types for pneumatic tires, and comprises mechanism whereby the operations of winding the fabric, forming the 15 beads, and applying the gum, may be performed in the main mechanically instead of by hand as is at present customary.

The objects of my invention are to construct pneumatic tires, and, particularly, the 20 shoes thereof, by machine work; and to provide a simple and reliable machine for such purpose.

I will now proceed to describe my invention with reference to the accompanying 25 drawings, in which one type of machine embodying my invention is illustrated, and will then point out the novel features in claims.

In said drawings: Figure 1 shows a side elevation of my tire making machine; Fig. 2 shows a top view thereof; Fig. 3 shows a transverse section thereof through the chuck and core; Fig. 4 shows an elevation of the inner side of one of the side plates of the chuck; Fig. 5 shows a front elevation of the 35 chuck; Fig. 6 is a detail view, more or less diagrammatic, illustrating the action of the presser rollers; the view showing a transverse section of the core with the said rollers in co-operative proximity thereto; Fig. 7 is a view illustrating more or less diagrammatically the action of the spaders on the 40 fabric; the view showing a cross section of the core and of a layer of the fabric thereon, and showing in operative position, one of the spaders; Fig. 8 is a detail view illustrating the action of the mechanism for applying continuous beads to a shoe during the 45 process of formation thereof; the view showing in elevation a portion of the core looking from the center of rotation outward, and showing the bead-applying rolls in co-operative proximity to said core; Fig. 9 is another detail view illustrating the action 50 of the rollers for applying continuous beads, the view being a section on the line v—v of

Fig. 8; Fig. 10 is a detail view illustrating means for rolling the fabric over the bead, after the latter has been applied, and for insuring accurate form of the bead; the view showing a transverse section of the core, looking from the center of rotation outward, and showing one of the said rolls in co-operative proximity to the core; Fig. 11 shows a cross section of the "carcass" 60 of the tire after application of the beads and after the application of the fabric covering outside of the beads, the view showing the carcass after the action of the forming rollers and trimming knives thereon; Figs. 12 and 13 illustrate means for applying endless beads to tires, Fig. 12 showing a 65 side elevation of the core with a tire in process of formation thereon, and with a form in proximity thereto for applying a bead, and Fig. 13 showing a transverse section of the same parts, two of these forms being shown in co-operative proximity to the core, for applying beads to opposite sides of the shoe; Fig. 14 is a detail elevation and partial section of the traverse saddles carrying the tool arms, the view being a section on the line w—w of Fig. 1, looking in the direction of the arrows. Fig. 15 is a detail view illustrating the swivel-connection of the tools to the tool carrying arms; Fig. 16 70 is a detail elevation of the tension-applying and adjusting device; Fig. 17 is a detail 75 transverse section of one form of tire shoe such as may be formed in the machine herein described.

In forming tire shoes by means of the machine shown in the above drawings, the method of operation is as follows: A core upon which the carcass of the shoe is to be formed, is mounted on a suitable rotatable 80 chuck, and the end of a strip of tire-fabric saturated with rubber cement or other suitable material, is drawn from a supply roll and is applied to the surface of the core, the latter having previously been covered 85 with cement, so that the fabric, when applied to it, adheres to it. The successive layers of this fabric on the supply roll are separated from one another by an interwound wrapper strip, and as the fabric is 90 drawn from the supply roll, as hereinafter described, this wrapper strip winds upon a wrapper roll, being thereby drawn away 95 from the fabric before the latter reaches the core. Means hereinafter described are 100 105 110

provided for maintaining tension upon the fabric, as it is drawn from the supply roll, and for regulating such tension. The end of the fabric strip having been applied to the core, as just described, the core is rotated by suitable means, the strip being thereby drawn from the supply roll and wound upon the surface of the core. In some cases the tension on the fabric is relied upon to insure close winding of the fabric on the core, and of successive layers of the fabric upon the layers beneath, while in other cases pressure rollers are provided in addition for rolling down the fabric upon the core as the winding proceeds. After a suitable number of layers of the fabric have been wound upon the core in this manner, (usually after two layers of the fabric have been so wound upon the core) beads are applied to the two sides of the partly formed carcass, in the manner hereinafter described, and the winding of the fabric is continued, so that the fabric covers these beads as well as the layers of fabric already wound upon the core. During the rolling of the first layers of the fabric upon the core, and also during the winding of the further layers of fabric after the application of the beads, the fabric is pressed in tightly against the under side of the core, by suitable tools termed spades, operated by hand; and suitable bead rolls also press upon the portion of the carcass immediately outside of the beads, to form accurately these portions of the shoe. After a sufficient number of layers of fabric have thus been applied to the core, the strip of fabric is cut, the end pressed down tightly upon the layers of fabric beneath, and then one or more layers of gum are applied to the outer portion of the tire to form what is termed the "padding". This padding usually covers the entire outer surface of the carcass as so far formed, from the bead on one side thereof to the bead on the other side thereof. If a gum strip of proper thickness is used, only one layer of this padding is required. Such layers of gum may be applied by hand, or, and preferably, may be applied by substituting in the machine, for the fabric supply roll previously in place therein, another supply roll carrying a gum strip. This gum strip is wound upon the partly formed carcass in the same manner as previously described with reference to the winding of the fabric. Another strip of gum, somewhat narrower, and, usually, considerably thicker than the strip for forming the padding, is then applied to what is to be the tread surface of the shoe, in a similar manner. The construction of the shoe is then complete, and it is ready for curing, which latter is done in the ordinary manner and is not involved in my present invention.

In the drawings, 1 designates the shaft upon which the chuck is mounted, 2 a frame in which said shaft is mounted revolvably, 3 a gear wheel on said shaft, 4 a pinion intermeshing with said gear 3 and mounted upon a shaft 5, and 6, 6 designate loose and tight belt pulleys on said shaft, the tight pulley serving to drive shaft 1 through the gears.

7 designates the chuck. The particular chuck shown is of novel construction and will be described more in detail later. 8, 8 designate the jaws of said chuck.

9 designates the tire-forming core which is customarily a hollow iron annulus, as shown, and which has externally a form corresponding to the form to be given internally to the shoe.

10 designates the supply roll from which the fabric strip is drawn, and 11 designates the shaft upon which said roll is mounted.

12 designates the fabric strip. 13 designates the wrapper roll upon which the wrapper of the said fabric strip is wound as the strip itself passes to the core.

14 designates the shaft upon which said wrapper roll is mounted, and 15, 15 designates guides in which said shaft 14 may move radially to or from the supply roll.

In starting the making of a tire in this machine, the fabric strip is led from the supply roll, as previously described, and its end applied to the surface of the core as previously described. The core is then caused to rotate, and as it rotates workmen apply spades 16 (Fig. 7) by hand, to the fabric strip, pressing the fabric closely against the under side of the core, as illustrated in Fig. 7.

In some cases the tension on the fabric strip is relied upon to secure the desired tightness of winding of said strip upon the core; while in other cases presser rolls 17, 17 (Fig. 6) are employed to press the fabric more firmly against the core. These rolls 17, when employed, are mounted upon branches 18 of a forked lever 19, and by means hereinafter described the pressure of these rolls is regulated. The mounting of the said lever is also such, as hereinafter described, that as the diameter of the carcass of the tire gradually increases, this lever can retreat slightly, so that substantially the same pressure is exerted by said rolls upon the carcass at all times. The rolls are placed obliquely as shown particularly in Fig. 6, and one of the rolls is located slightly in rear of the other and slightly overlaps the track of the first roll so that the entire upper surface of the carcass is subjected to the pressure of these rolls. For regulating the tension upon the fabric strip, I employ a friction bearing box 20 (Fig. 16) which may be set up to any desired degree of tension by means of screws 21. After a sufficient number of layers of the fabric (usually two

layers) have been applied to the core in this manner, the customary beads 22 are introduced. I may employ endless beads, in which case the bead rings, previously formed, are placed upon the peripheries of forms 23 (Figs. 12 and 13) and these forms are pressed against the partly formed carcass as shown in Fig. 13. These forms have open centers which fit upon the chuck as indicated in Figs. 12 and 13. Or, I may employ a continuous bead stock in which case rolls 24 (Figs. 2, 8 and 9) are provided so mounted that they may be moved close up against the partly formed carcass and may serve as guides to guide the bead stock in place.

In Fig. 8 numbers 25 designate continuous bead stock drawn from sources of supply not shown, and guided by the rolls 24 against the carcass. In using this continuous bead stock the end of the stock is passed partly around the corresponding guide roll 24, and pressed against the partly formed carcass in the place where the bead is to be applied, where it will adhere, owing to the bead stock being sticky. The core is then rotated and as it rotates the rolls 24 guide the bead stock in place. When the bead is practically complete, the bead stock is cut at the proper point so that where cut the end will abut against the initial end of the bead.

After the beads have been applied in either of the manners described, or in any other suitable manner, further layers of fabric 12 are applied to the carcass in the manner previously described, until a sufficient thickness of fabric has been applied to the core; these further layers being spaded in place in the manner previously described, the spading being done over the beads as well as down to them; and to perfect the form of the carcass, at and around the beads, forming rolls 26 (Figs. 2 and 19) are employed, these rolls being held against the beads in the manner hereinafter described.

A padding layer 27 of gum is then applied over the layers of fabric previously applied. This padding layer may be applied by hand or it may be drawn from another supply roll, mounted upon the shaft 11 in place of the supply roll 10 previously on said shaft; and in applying the padding layer the presser rolls 17, may or may not be used, as preferred. Usually a single thickness of padding is all that is required, though if desired further thicknesses may be applied. A tread strip 28 of gum is then applied to the carcass, in the same manner; that is to say, either by hand, or by drawing it from a suitable supply roll. The shoe is then finished and is ready for curing.

After the application of the desired number of layers of fabric, following the application of the beads, and before the application of the padding, the edges of the carcass are

trimmed to bring the tire to proper size and to get the proper shape at its edges. For this purpose trimming knives 29 are employed, said knives being supported as hereinafter described.

70

In applying the continuous beads as illustrated in Figs. 8 and 9, I employ, in addition to the main guide rolls 24, other guide rolls 30, spring pressed toward guide rolls 24 and which serve to hold the bead stock 75 against said guide rolls.

The bead applying rolls 24, if employed, the bead forming rolls 26, and the trimming knives 29, are mounted upon arms 31, 32 and 33 respectively, mounted to slide longitudinally in other arms, 34, 35 and 36 respectively, pivoted to a traverse saddle 37 mounted on guides of a carriage 38. There being arms 34, 35 and 36 on each side of the core, there are two of these saddles supporting two arms, as shown particularly in Fig. 2, and to move said saddles toward and from each other, an adjusting screw 39, and hand wheel 40 (Fig. 14) are employed, the screw having right hand and left hand threaded portions engaging the two saddles 37. The carriage 38 is mounted in guides of a frame or pedestal 41 and is arranged to be moved toward and from the core by means of a screw 42 and hand wheel 43. The lever 19 carrying the presser rolls 17, is pivoted to blocks 44 mounted to slide up and down in guides 45 on the frame 41, and clamping bolts 46 are provided for clamping these blocks 44 in any position in which they may be adjusted. At the rear of this lever 19, is a stud 47 movable up and down in a socket in a block 48 having a swivel connection at 49 to the carriage 38, and in this socket there is a spring 50 tending to press the presser 105 rollers against the carcass. By means of a nut 51 the stud 47 may be screwed up or down, so regulating the pressure exerted by the spring.

For pressing the trimming knives 29, the bead forming rolls 26 or the guide rolls 24, against the carcass, I employ eccentric rollers 52 mounted on hand levers 53 themselves mounted on vertically adjustable stands 54 comprising a base 55 and a vertically adjustable member 56. To adjust the stands vertically their vertically movable members 56 are provided with ratchet teeth 57, and spring actuated pawls 58 are provided to engage these ratchet teeth and hold said members 56 in any position to which they may be adjusted. A hand lever 53 having been raised, by the means described, to a position opposite one or another of the arms 34, 35, or 36, it is held there by the action of the pawl 58, and then by actuating the lever 53 the eccentric roller 52 may be pressed against the arm 34, or 35, or 36, so pressing the tool carried thereby against the carcass. The rollers 24 and 26 are mounted upon 130

their respective arms 32 and 33, by means of yokes 59 (Fig. 15) having swivel connection, as shown, with their respective arms, so that the said rollers may be adjusted properly against the carcass. The knives 29 have a similar swivel mounted on their arms 31.

The chuck 7, by which the core is supported, comprises two disks 60 and 61 (Fig. 10) provided with guides for the clutch jaws and these jaws are provided with teeth engaging spiral ribs 62 formed on disk plate 61 of the clutch. Plate 60 is secured to shaft 1 by means of a set screw 63. Plate 61 is mounted upon a hub 64 similarly secured to the shaft. It will be apparent that by rotating plate 61 upon its hub 64, the clutch jaws may be moved in or out as desired.

To obviate roughening of the tire during the process of formation, the presser rolls 17 are preferably formed as a plurality of disks separately rotatable, as indicated in Fig. 6. For similar reasons the bead-forming rolls 26 are preferably formed in two 25 separately rotatable sections 26^a and 26^b, as indicated in Fig. 10.

What I claim is:

1. A tire forming machine comprising in combination a rotatable ring-shaped core, upon which the tire may be formed, a pedestal in front of and at a distance from said core, pressure-rollers arranged to bear upon the surface of the forming tire, said rollers mounted to operate on the main tread portion of the tire being formed, and means pivotally mounted on said pedestal and movable from and toward said core and supporting said rollers.

2. A tire forming machine comprising in combination a rotatable ring-shaped core upon which the tire may be formed, a pedestal in front of and at a distance from said core, presser-rollers arranged to bear upon the surface of the forming tire, said rollers mounted to operate on the main tread portion of the tire being formed, and supporting means pivotally mounted on said pedestal and movable toward and from the said core and supporting said rollers, said supporting means extending rearwardly beyond its point of the pivotal connection to said pedestal, and a compression spring carried by the pedestal and acting on such rearwardly extending portion of said supporting means and adapted to press the same toward the core.

3. A tire forming machine comprising in combination a rotatable ring-shaped core, upon which the tire may be formed, presser-rollers arranged to bear upon the surface of the forming tire, and a lever supporting said rollers and movable toward and from said core, said two rollers located in the main on opposite sides of the core, one of said rollers

being somewhat in rear of the other and 65 overlapping the track of such other roll.

4. A tire forming machine comprising in combination a rotatable ring-shaped core, upon which the tire may be formed, presser-rollers arranged to bear upon the surface of 70 the forming tire, and a bifurcated lever for supporting said rollers, the branches thereof extending toward the sides of the core, said rolls being mounted at the ends of said branches, one roll being somewhat in rear 75 of the other roll, and overlapping the track of such other roll.

5. A tire forming machine comprising in combination a ring core, and tool-supporting means comprising a standard, a carriage 80 mounted thereon and movable toward and from said core, and a saddle mounted to slide transversely on said carriage, and tool carrying arms pivoted to said saddle, the axes of the pivots of said arms being approximately perpendicular to the plane of 85 the movement of said carriage.

6. A tire forming machine comprising in combination a rotatable ring core, a pedestal comprising a carriage movable toward and 90 from said core in a direction substantially parallel to the plane of rotation of said core, said carriage provided with a guide, transversely arranged with respect to said core, saddles mounted to slide on said guide, and 95 tool-arms pivoted to said saddles and arranged to swing laterally on their pivots well out of co-operative proximity to said core, the axes of the pivots of said arms being approximately perpendicular to the 100 plane of the movement of said carriage.

7. A tire forming machine comprising in combination a rotatable ring core, a pedestal comprising a carriage movable toward and from said core in a direction substantially parallel to the plane of rotation of said core, said carriage provided with a guide, transversely arranged with respect to said core, saddles mounted to slide on said guide, tool-arms pivoted to said saddles and 105 arranged to swing laterally on their pivots well out of co-operative proximity to said core, and means for moving said saddles toward and from the plane of rotation of 110 said core.

8. A tire forming machine comprising in combination a ring core, tool-supporting means comprising a standard and one or more arms pivoted thereto, and adapted to carry tools, and means for pressing one or 120 more of the tools so carried against the work, comprising a lever and a pivotal support therefor, said lever adapted to press against one of said arms and thereby force it toward the work.

9. A tire forming machine comprising in combination a ring core, tool supporting means comprising a standard and one or

more arms pivoted thereto, and adapted to carry tools, and means for pressing one or more of the tools so carried against the work, comprising a lever, a pivotal support therefor, and an eccentric roller on said lever adapted, by the movement of the lever, to be caused to press against one of said arms.

10. A tire forming machine comprising in combination a rotatable ring core, a pivotally mounted tool arm arranged to swing toward and away from said core, and bead-applying means swivel-connected to said arm, and comprising a grooved bead-guiding and -applying roll and a second roll having an axis substantially parallel to that of the first roll and arranged close to the periphery of the first roll and adapted to hold the bead strip in place in the groove of said first roll, the axis of said swivel-connection being approximately perpendicular to the plane of rotation of said core when the bead-applying means is in working position.

11. A tire forming machine comprising in combination a rotatable ring core, a pedestal comprising a carriage movable toward and from said core in a direction substantially parallel to the plane of rotation of said core, said carriage provided with a guide, trans-

versely arranged with respect to said core, ³⁰ saddles mounted to slide on said guide, and tool-arms pivoted to said saddles and arranged to swing on their pivots well out of coöperative proximity to said core, the axes of the pivots of said arms being approximately perpendicular to the plane of the movement of said carriage.

12. A tire forming machine comprising in combination a rotatable ring core, a pedestal comprising a carriage movable toward and ⁴⁰ from said core in a direction substantially parallel to the plane of rotation of said core, said carriage provided with a guide, transversely arranged with respect to said core, ⁴⁵ saddles mounted to slide on said guide, tool-arms pivoted to said saddles and arranged to swing on their pivots well out of coöperative proximity to said core, and means for moving said saddles toward and from the plane of rotation of said core. ⁵⁰

In testimony whereof I have signed this specification in the presence of two subscribing witnesses.

THOMAS J. WHALEN.
